UNITED STATES PATENT OFFICE.

LÉON PARENTEAU, OF ST. GEORGE DE CHAMPLAIN, QUEBEC, CANADA.

BRIDLE BIT.

Application filed July 11, 1924. Serial No. 725,357.

To all whom it may concern:

Be it known that I, LÉON PARENTEAU, subject of the King of Great Britain, residing at St. George de Champlain, in the Province of Quebec, Canada, have invented certain new and useful Improvements in Bridle Bits; and I do hereby declare that the following is a full, clear, and exact description of the invention, such as will enable others skilled in the art to which it appertains to make and use the same.

The present invention pertains to a novel bridle bit adapted for use with the harness for a horse.

As is well known by drivers of horses, when the driving reins are pulled for the purpose of drawing the bit into the corners of the horse's mouth, the horse grasps the bit in his teeth and prevents it from accomplishing the desired object. The present invention aims to overcome this difficulty and accordingly provides for a bit proper or mouth piece which cannot be grasped in the teeth of the horse. In the accomplishment of this object, the invention comprises a shell adapted to enclose the mouth piece. The cheek pieces are attached to the ends of the mouth piece and support the shell for movement with relation thereto. Thus, the horse can clench only the shell in his teeth, and the mouth piece together with the cheek pieces are drawn inwardly when the driving reins are pulled. When the reins are released, the yielding connection between the shell and the cheek pieces operates to return the mouth piece into the shell.

The invention is fully disclosed in the following description and in the accompanying drawings in which:

Figure 1 is a side view of a horse, showing the device applied;

Figure 2 is a side elevation of the device;

Figure 3 is a similar elevation, showing the cheek pieces and mouth piece drawn inwardly;

Figure 4 is a front elevation of the device partly in section;

Figure 5 is a fragmentary longitudinal section of the device in extended position; and,

Figure 6 is a section on the line 6—6 of Figure 4.

Reference will now be had to these views by means of like characters which are em-

ployed to designate corresponding parts throughout.

The cheek pieces of the device are indicated by the numeral 1 and are each provided with slots 2 and 3 for the accommodation of the cheek strips 4 and the driving reins 5 respectively, as shown in Figure 1. A mouth piece 6 has its ends received in and secured to the lower portions of the pieces 1, holding the latter parallel to one another and perpendicular to the piece 6, as shown in Figure 4. Each cheek piece is formed with a tube or sleeve 7 containing a rod 8 formed at its upper end with a disc 9 and at its lower end with a head 10. Each rod is surrounded by an expansion spiral spring 11 engaging the corresponding disc 9 and end of the mouth piece 6.

A shell 12 is carried at the lower ends of the rods 8, engaging the heads 10 thereof and adapted to enclose the mouth piece 6, as shown in Figure 6. The shell is formed with a plurality of transverse apertures 13 for the flow of saliva therethrough.

In use, when the driving reins 5 are pulled, the horse grasps the shell 12 in his teeth for the purpose of preventing the mouth piece from being drawn into the corners of his mouth. Since the mouth piece is contained within the shell and movable with relation thereto, the cheek pieces will be drawn inwardly, carrying with them the mouth piece 6 against the action of the springs 11. The rods 8 remain immovable since they are held by the shell 12. When the tension on the reins 5 is released, the mouth piece 6 returns into the shell under the action of the springs 11.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A bridle bit comprising a mouth piece, cheek pieces secured at the ends thereof, and a shell adapted to enclose said mouth piece and yieldably supported by said cheek pieces.

2. A bridle bit comprising a mouth piece, cheek pieces secured at the ends thereof,

tubes formed on said cheek pieces, a shell adapted to enclose said mouth piece, rods secured to the ends of said shell and slidably passed through said mouth piece, said rods being yieldably held in said tubes.

3. A bridle bit comprising a mouth piece, cheek pieces secured at the ends thereof, tubes formed on said cheek pieces, a shell adapted to enclose said mouth piece, rods secured to the ends of said shell and slidably passed through said mouth piece into said tubes, discs carried by said rods within said tubes, and springs surrounding said rods and engaging said discs and mouth piece.

4. A bridle bit comprising a mouth piece, cheek pieces secured at the ends thereof, tubes formed on said cheek pieces, a shell adapted to enclose said mouth piece, rods secured to the ends of said shell and slidably

passed through said mouth piece, said rods being yieldably held in said tubes, said shell having a plurality of apertures formed transversely therethrough.

5. A bridle bit comprising a mouth piece, cheek pieces secured at the ends thereof, tubes formed on said cheek pieces, a shell adapted to enclose said mouth piece, rods secured to the ends of said shell and slidably passed through said mouth piece into said tubes, discs carried by said rods within said tubes, and springs surrounding said rods and engaging said discs and mouth piece, said shell having a plurality of apertures formed transversely therethrough.

In witness whereof I have hereunto set my hand.

LÉON PARENTEAU.
